[57] ABSTRACT

The centralizer comprises a pair of mutually engaging arms, movable by a hydraulic-fluid powered piston rod, for closure about a drill rod. The arms have resiliently loaded, extending pins therein which engage to inhibit an abutting closure of the arms upon each other, when powered by a first hydraulic supply. When powered by a second hydraulic supply, the pins are caused to retract into the arms, and the arms do close to an almost abutting disposition. In this latter operation, the arms grip and restrain a drill rod coupling disposed therebetween to facilitate a coupling (or uncoupling) of a drill rod therewith (or therefrom).

HYDRAULIC CENTRALIZER

This invention pertains to drill rod handling means, and in particular to a device, fluid-powered, which centralizes drill rods, when mounted on a drilling machine feed guide structure.

Fluid-powered drill rod centralizers are known, and usually comprise hydraulic- or pneumatic-actuated arms which abuttingly close upon one another and cooperate to define an aperture therebetween in which to centralize the drill rod. The known centralizers, then, have a single operative positioning, and lack any facility for restraining a drill rod coupling while simultaneously providing "centralizing" for a drill rod coupled to, or couplable with, the restrained coupling.

It is an object of this invention to provide a centralizer for drill rods which will provide for remote operation.

It is another object of this invention to provide a centralizer having means which grip the coupling and restrain it against rotation while the drill rod is left unrestrained.

A feature of this invention comprises a pair of pivotally mounted centralizing arms, movable by a fluid-powered motor, to two, operational, predetermined positions for closure upon each other to centralize a drill rod therebetween. In one of the operational positions, the arms "centralize" a drill rod and coupling unit; in the other operational position, the arms grip and restrain a drill rod coupling disposed therewithin while setting apart, circumferentially, from a drill rod therewithin, coupled to the restrained coupling, or from a rod placed therewithin for coupling thereof to the restrained coupling.

Further objects and features of this invention will become more apparent by reference to the following description thereof taken in conjunction with the accompanying figures, in which:

FIG. 1 is a side elevational view of an embodiment of the novel centralizer, partly in section and broken away;

FIG. 2 is bottom view of the FIG. 1 embodiment, taken along the plane 2—2 shown in FIG. 1; and

FIGS. 3, 4 and 5 are schematic representations of the aforesaid embodiment in three functional positions.

As shown in FIGS. 1 and 2, the novel centralizer 10, according to an embodiment thereof, comprises a pair of centralizer arms 12 which house centralizer bushings 14 which are retained by bolts 16, and a plunger or pin 18 which is spring-loaded by disc springs 20 against a shoulder 22 and retained by plate 24.

The centralizer arms 12 also support crosshead or key pins 26 which provide pivotal support for crossheads or keys 28. The arms 12 are pivotally mounted to a centralizer body 30 through bearings 32 and 34 and cantilever pins 36. The body 30 also mounts a hydraulic cylinder 38 with a piston rod 40. The end of the piston rod 40 which is more proximate to the arms 12 defines a generally rectangular bar 42 which has crosshead or keyway slots 44 formed in lateral surfaces thereof. The sizing or dimensioning of the slots 44 is such that the upper end of piston rod 40 is straddled by the centralizer arms 12, and the slots 44 slidably receive the keys 28 therewithin.

The hydraulic cylinder 38 has a hydraulic fluid adapter 46 connected thereto for fluid-communicating with one side of the piston (not shown) and another adapter 46a connected thereto for fluid-communicating with the other side of the piston. Adapter 46 is connected by conduit 48 to a closed-center, four way valve 50 serviced with approximately 200 psi hydraulic pressure from a supply S-1 and by conduit 52 to open-close valve 54 which is serviced with approximately 2,000 psi hydraulic pressure from a supply S-2. Adapter 46a is connected by conduit 56 to valve 50. The body 30 is mounted to a drilling machine feed guide structure 58 (only a portion of which is shown).

The novel centralizer 10 operates as follows to centralize a drill rod 60 and to support the drill rod coupling 62 therein. With valve 54 in closed position (as shown) valve 50 can be positioned to provide 200 psi hydraulic pressure, from supply S-1, through conduit 48 and adapter 46 to one side of the piston (not shown) of the hydraulic cylinder 38 causing piston rod 40 to advance, i.e., extend. The hydraulic force is transmitted by the keyway slots 44 to the keys 28—the latter being pivotally connected, through pins 26 to centralizer arms 12. Since arms 12 are pivotally mounted to the body 30 by pins 36, the arms 12 are caused to rotate around pins 36 in a modified "scotch yoke" action until the ends of pins 18 make contact. The 200 psi hydraulic pressure of supply S-1 is not sufficient to compress springs 20, thus a first bore area 64 formed of the centralizer bushings 14 provides the centralizing for the drill rod 60. A second bore area 66 formed of the centralizer bushings 14 is larger than coupling 62 and, in conjunction with a shoulder 68 formed of the junction of bores 64 and 66 defines a socket cavity for assured support of the coupling 62, and of the drill rod—upon the rod 60 being threadedly coupled to the coupling 62.

The foregoing discussion described a not unconventional functioning of the centralizer 10 in which the arms 12 are moved to a given predetermined and operational position, in which they close upon each other, into adjacency, to centralize a drill rod 60 therebetween, or a drill rod coupling 62, or both (i.e., a drill rod 60 with coupling 62).

This given, operational positioning is depicted in FIGS. 2 and 3. It is to be noted that the foremost extending portion of the bar 42, as FIG. 3 evidences, sets in a disposition removed a distance of X from the bushing-holding terminations of arms 12. As noted, the supply S-1 is not sufficient to overcome the bias of springs 20, thus the arms 12 set apart with a space S therebetween.

In this operational positioning, the novel centralizer 10 simply centralizes the rod 60 and/or coupling 62 disposed therebetween and, with bore 64 directed downwardly and bore 66 upwardly—as though for overhead drilling, shoulder 68 supports the coupling 62, and any rod 60 coupled thereto, slidably therein against gravity. The i.d. surfaces of bores 64 and 66 are set apart from the o.d. surfaces of the coupling 62 (and any such rod 60 disposed in bore 64).

This inventive centralizer 10, however, has a second predetermined and operational positioning in which the arms 12 grip and restrain the coupling 62 against movement within bore 66. The selective operation of

the centralizer 10 for disposition in this second positioning is as follows.

With valve 50 in closed center position (as shown), valve 54 can be positioned to provide 2000 psi hydraulic pressure, of supply S-2, through conduit 52 and adapter 46 to the same one side of the piston of hydraulic cylinder 38. The hydraulic force is transmitted as described in the foregoing operation—in which the device “centralized,” however, the force is now sufficient to compress springs 20 and to substantially eliminate the clearance space S. Now, the bore 66 grips and restrains the coupling 62. Bore 64 does not, however, restrain the drill rod 60; thus, the rotation drive motor of the drilling machine (not shown) can couple or uncouple the drill rod 60 to or from the gripped and restrained coupling 62.

In this coupling-gripping operation, the arms 12 make an almost abutting closure AC (FIG. 4) upon each other, because the hydraulic force is sufficient both to cause pins 18 to retract into the arms 12 and to advance the bar 42 further than that disposition which the bar 42 assumed in “centralizing” operation. As FIG. 4 illustrates, the bar 42 advances to a distance of X/2 from the bushing-holding terminations of arms 12. Even with this near abutting closure of arms 12, the dimension of bore 64 is sufficient to accommodate a drill rod 60 slidably therein. The near abutting closure of arms 12, however, causes the i.d. surfaces of bore 66 to engage and grip the o.d. surfaces of the coupling 62 against rotary and axial movement therein.

The o.d. of a given, standard-size coupling, as represented by coupling 62, is slightly greater than the i.d. of bore 66, even with piston rod 40 and bar 42 fully extended under the influence of the 2,000 psi hydraulic supply S-2. Accordingly, during the coupling-gripping operation the arms 12 stop just short of abutting closure, to assure that the maximum hydraulic force is utilized in the gripping action.

Finally, the novel centralizer 10 is selectively operative to open the arms 12 widely apart to permit a drilling machine (not shown) to travel therethrough and therebetween. This operation is effected as follows.

With valve 54 in the closed position (as shown), valve 50 can be positioned to provide 200 psi hydraulic pressure from supply S-1 through conduit 56, and adapter 46a, to the opposite side of the piston (not shown) of the hydraulic cylinder 38 causing piston rod 40 to retract. By the reverse procedure (to that described in connection with the “centralizing” operation) the force applied through keys 28 again initiates a modified “scotch-yoke” motion. Arms 12 again pivot about pins 36 and open to the positioning indicated in FIG. 5. This is sufficiently wide to permit the front head 55 of the drilling machine (not shown) to pass through the open centralizer arms 12.

While I have described my invention in connection with a specific embodiment thereof it is to be clearly understood that this is done only by way of example and not as a limitation to the scope of my invention as set forth in the objects thereof and in the accompanying claims. For example, I have disclosed my invention for use with hydraulic fluid for the enabling thereof. Actually, my novel centralizer will operate to “centralize” with a pneumatic supply of energy—although pneumatic energy is inadequate to effect the gripped

restraint of the drill rod coupling. Further, bushings 14 are shown disposed to support a drill rod coupling 62 on the shoulder 68 thereof for upward drilling. Yet, bushings 14, which define bores 62 and 64, and also have a coupling-access beveled surface 70, can be turned end-for-end in arms 12, by removing the bushing mounting bolts 16, and be fixed in arms 12 in the opposite direction. Then shoulders 68 will support a coupling 62 for downward drilling. These and other teachings, which those skilled in the art to which this invention pertains will glean from my disclosure, are comprised by the spirit of my invention.

I claim:

1. A fluid-powered drill rod centralizer, comprising:
a body;
a plurality of means mounted to said body for centralizing a drill rod, wherein
at least one means of said plurality is movable, relative to other means of said plurality, to a number of not less than two, operational, predetermined positions for closure upon said other means to centralize a drill rod therebetween;
fluid-responsive motor means;
means intercoupling said motor means and said plurality of centralizing means for effecting movement of said one means by said motor means; and
means supplying powering fluid to said motor means, operative for disposing said one means in any one of said positions; wherein
all means of said plurality of centralizing means are movable, to a number of not less than two, operational, predetermined positions;
said intercoupling means couples said motor means and said all centralizing means for effecting movement thereof by said motor means;
said supplying means comprises
a plurality of sources of pressurized fluid,
said sources of the plurality thereof defining supplies having disparate fluid pressures; and
control means operative for supplying pressurized fluid from any one of said sources to said motor means to effect movement of said all centralizing means to given operational positions of said number of positions.

2. A centralizer, according to claim 1, wherein:
said centralizing means comprises a plurality of arms each having relieved surfaces, and said relieved surfaces are cooperative, upon closure of said arms upon each other, to define an aperture therebetween within which to centralize said drill rod.

3. A centralizer, according to claim 1, wherein:
said one means is cooperative with said other means, upon movement thereof to one of said positions, simultaneously to grip and restrain a coupling of a drill rod positioned therebetween, while defining a circumferential space about the drill rod and between the drill rod and said plurality of centralizing means to facilitate a withdrawal of said drill rod from such a gripped and restrained coupling thereof.

4. A fluid-powered drill rod centralizer, comprising:
a body;
a plurality of means mounted to said body for centralizing a drill rod, wherein

at least one means of said plurality is movable, relative to other means of said plurality, to a number of not less than two, operational, predetermined positions for closure upon said other means to centralize a drill rod therebetween; 5
 fluid-responsive motor means;
 means intercoupling said motor means and said plurality of centralizing means for effecting movement of said one means by said motor means; and means supplying powering fluid to said motor means, operative for disposing said one means in any one of said positions; wherein
 all means of said plurality of centralizing means are movable to a number of not less than two, operational, predetermined positions; 10
 said intercoupling means couples said motor means and said all centralizing means for effecting movement thereof by said motor means;
 said centralizing means comprises a plurality of arms each having relieved surfaces, and said relieved surfaces are cooperative, upon closure of said arms upon each other, to define an aperture therebetween within which to centralize said drill rod; and 15
 at least one of said arms has means automatically operative to inhibit an abutting closure of any surface of said one arm upon any surface of another of said arms.
 5. A centralizer, according to claim 4, wherein: 20
 said inhibit means comprises means projecting from a surface of said one arm for impingement thereof upon said another arm.
 6. A centralizer, according to claim 5, wherein: 25
 said projecting means comprises a pin slidably mounted within said arm; and
 said inhibit means further comprises means disposed within said arm for urging said pin in projection from said arm.
 7. A centralizer, according to claim 4, wherein: 30
 said relieved surfaces are arcutely defined.
 8. A centralizer, according to claim 7, wherein: 35
 said relieved surfaces cooperatively define a plurality of substantially annular areas with differing cross-sectional radii.
 9. A centralizer, according to claim 8, wherein: 40
 said differing radii areas cooperatively define a plurality of differing diameter sections within said aperture, and wherein:
 upon movement of said centralizing means to a given one of said positions, one differing diameter section of the plurality thereof grips and restrains a coupling of a drill rod positioned therewithin while simultaneously, other sections of the plurality thereof set apart from the positioned drill rod to facilitate withdrawal of said drill rod from the coupling thereof gripped and restrained within said one section. 45
 10. A centralizer, according to claim 8, wherein: 50
 said differing radii areas are cooperative to define a plurality of differing diameter sections within said aperture; and
 upon movement of said arms to a given one of said positions, one differing diameter section of the plurality thereof grips and restrains a coupling of a drill rod disposed therewithin while simultaneously 55
 60
 65

other sections of the plurality thereof define a space therebetween and therewithin to facilitate an insertion of a drill rod into said space for the joining of such an inserted rod with a coupling therefor restrained within said one section.
 11. A centralizer, according to claim 4, wherein: 70
 said relieved surfaces further cooperate to define a substantially annular shoulder therewithin, upon closure of said arms upon each other, to receive and arrest a coupling of a drill rod disposed therewithin against gravitational-induced movement from said aperture.
 12. A fluid-powered drill rod centralizer, comprising: a body;
 a plurality of means mounted to said body for centralizing a drill rod, wherein
 at least one means of said plurality is movable, relative to other means of said plurality, to a number of not less than two, operational, predetermined positions for closure upon said other means to centralize a drill rod therebetween; 75
 fluid-responsive motor means;
 means intercoupling said motor means and said plurality of centralizing means for effecting movement of said one means by said motor means; and means supplying powering fluid to said motor means, operative for disposing said one means in any one of said positions; wherein
 said centralizing means have at least first and second portions which, upon closure of said one means thereof upon said other means thereof in said positions, become juxtaposed; and
 said one means is cooperative with said other means, upon movement thereof to one of said positions, to grip and restrain a drill rod coupling disposed between said first, juxtaposed portions of said centralizing means, and simultaneously, to define a space between said second, juxtaposed portions of said centralizing means to facilitate an insertion of a drill rod into said space for the joining of such an inserted rod with a coupling therefor restrained between said first portions.
 13. A fluid-powered drill rod centralizer, comprising: a body;
 a plurality of means mounted to said body for centralizing a drill rod, wherein
 at least one means of said plurality is movable, relative to other means of said plurality, to a number of not less than two, operational, predetermined positions for closure upon said other means to centralize a drill rod therebetween; 80
 fluid-responsive motor means;
 means intercoupling said motor means and said plurality of centralizing means for effecting movement of said one means by said motor means; and means supplying powering fluid to said motor means, operative for disposing said one means in any one of said positions; wherein
 said supplying means comprises
 a plurality of sources of pressured fluid,
 said sources of the plurality thereof defining supplies having disparate fluid pressures; and
 control means operative for supplying pressured fluid from any one of said sources to said motor means to effect movement of said one means to
 85
 90

given operational positions of said number of positions.

14. A fluid-powered drill rod centralizer, comprising: a body; a plurality of arms mounted to said body for movement thereof, relative to said body, to a number of not less than two, operational, predetermined positions for closure thereof upon each other cooperatively to centralize a drill rod therebetween; 5 fluid-responsive motor means; means intercoupling said motor means and said plurality of arms for effecting movement thereof by said motor means; and means supplying powering fluid to said motor means, operative for disposing said arms for any one of 15 said positions; wherein said motor means comprises a fluid-actuated piston and cylinder assembly, said assembly having an extendable piston rod projecting therefrom; said rod has key-way-type of recesses formed in 20 lateral surfaces thereof; and said arms have key-type members coupled thereto in engagement with said recesses.

15. A centralizer, according to claim 14, wherein:

10

25

said key-type members are pivotally coupled to said arms; and said arms are pivotally coupled to said body.

16. A centralizer, according to claim 14, wherein said supplying means comprises a plurality of sources of pressured fluid; said sources of the plurality thereof defining supplies having disparate fluid pressures; and control means operative for supplying pressured fluid from any one of said sources to said motor means to effect movement of said arms to given operational positions of said number of positions.

17. A centralizer, according to claim 16, wherein: said arms have means automatically operative to inhibit an abutting closure of any surface of said one arm upon any surface of another of said arms; and at least one fluid source of the plurality thereof comprises a supply of fluid of a pressure sufficient to overcome said inhibit means, to cause an almost abutting closure of surfaces of said arms upon one another.
